(57) **CLAIM**

(21) Appl. No.: **29/199,457**

The ornamental design for an right side bezel for an avionics
flight display, as shown and described.

(22) Filed: **Feb. 13, 2004**

DESCRIPTION

(51) LOC (7) Cl. 12-99
(52) U.S. Cl. D12/345
(58) Field of Search D12/192, 345;
296/37.12, 70; 348/789, 836, 838

(56) **References Cited**

FIG. 1 is a front perspective view of a right side bezel for an
avionics flight display according to the present invention;
FIG. 2 is a front elevational view thereof;
FIG. 3 is a left side view thereof;
FIG. 4 is a right side view thereof;
FIG. 5 is a top plan view thereof; and,
FIG. 6 is a bottom plan view thereof.
